(57) **CLAIM**

The ornamental design for a bicycle rack, substantially as shown and described.

DESCRIPTION

FIG. 1 is a side elevation view showing a bicycle rack according to my new design, showing a bicycle in dashed lines, the bicycle not forming a part of my design;

FIG. 2 is a perspective view showing a bicycle rack;

FIG. 3 is another perspective view showing the bicycle rack;
FIG. 4 is a left side elevation view showing the bicycle rack, and showing in dashed lines a base bracket, not forming a part of the design;

FIG. 5 is a right side elevation view showing the bicycle rack and showing in dashed lines a base bracket, not forming a part of the design;

FIG. 6 is a top plan view showing the bicycle rack;

FIG. 7 is a bottom plan view showing the bicycle rack;

FIG. 8 is a front elevation of the bicycle rack;

FIG. 9 is a rear elevation of the bicycle rack;

FIG. 10 is a left side elevation view showing a slightly modified second embodiment of a bicycle rack according to my design; and,

FIG. 11 is a right side elevation view showing the modified bicycle rack of FIG. 10.
